UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

COMBINATION ELECTRICAL CONNECTER AND FIXTURE-SUPPORTING DEVICE.

Application filed December 6, 1920. Serial No. 428,444.

To all whom it may concern:

Be it known that I, REUBEN B. BENJAMIN, a citizen of the United States, residing at Chicago, in the county of Cook and State of Illinois, have invented new and useful Improvements in Combination Electrical Connector and Fixture-Supporting Devices, of which the following is a full, clear, concise, and exact description, reference being had to the accompanying drawing, forming a part of this specification.

My invention relates to electrical connector devices and more particularly to a combination electrical connector and fixture supporting device.

One of the objects of my invention is to provide such a device which will be strong and compact in construction, durable and efficient in use, and cheap to manufacture.

Further objects will appear from the detailed description to follow and from the appended claims.

In the drawings in which several embodiments of my invention are shown—

Fig. 1 is a vertical axial section showing a receptacle and a combination electrical connector and fixture supporting device associated therewith;

Fig. 2 is a section on the line 2—2 of Fig. 1;

Fig. 3 is a sectional view on the line 3—3 of Fig. 2;

Fig. 4 is a side elevation of a plug-in device;

Fig. 5 is a face view of the receptacle and supporting bracket;

Fig. 6 is a rear elevational view showing another form of fixture supporting bracket;

Fig. 7 is a part elevational, part sectional view showing another form of connection between the supporting device and fixture;

Fig. 8 is a front elevational view of part of the connecting bracket of Fig. 7;

Fig. 9 is a part elevational, part sectional view showing still another form of fixture connecting bracket;

Fig. 10 is a face view of the construction shown in Fig. 9; and

Fig. 11 is a section of the supporting plate substantially on the line 2—2 of Fig. 1.

Referring to Figs. 1 to 5 inclusive, the construction shown therein comprises an outlet box 15, an electrical receptacle 16, an electrical fixture 17, and a combination electri-

cal connector and fixture supporting device 55 for mechanically supporting the fixture 17 and electrically connecting it with the receptacle 16.

The receptacle 16 may be substantially the same as the receptacle shown in my copending application Serial No. 419,967 filed October 27, 1920, and will not be described in detail herein. It will be sufficient to state that, as shown in Fig. 2, it comprises an insulating base 19, a pair of receptacle contact devices 20 mounted on the base 19, and an insulating cover 21 for housing the contact devices 20, the contact devices 20 being located in suitable recesses in the insulating base 19 and cover 21. The cover 21 is provided with suitable funneled openings 22, for the entrance of the contact blades 23 into engagement with the contact devices 20. Each of the contact devices 20 comprise a substantially rigid contact member 24 and a yielding spring contact member 25, these contact members 24 and 25 extending parallel to each other and opposite to each other and transversely to the contact blade 23, the contact blade being received between these members.

The receptacle 16 is held in place on the cover 26 of the outlet box 15 by means of a pair of screws 27 which extend through registering openings in the insulating base 19, and cover 21, and are threaded into inwardly struck strap portions 28 on the cover or supporting member 26.

A suitable ornamental cover 29 may be provided which extends across the front of the main cover or support 26, this ornamental cover 29 being secured to the support 26 by means of a pair of screws 30, which extend through openings in the ornamental cover and are threaded into the inwardly struck straps 28.

The combination electrical connector and fixture supporting device comprises three main parts, a plug-in device 31 on which the contact blades 23 are mounted, for making the electrical connection; a connecting and supporting bracket member 32 for making the mechanical connection with the fixture 17, and an annular swiveled connecting member 33 for holding the plug-in device 31, and also the connecting bracket 32 in proper relative position with respect to each other and with respect to the recep-

tacle 16. This annular connecting member 33 may be of formed sheet metal and may be provided with a sort of cam acting bayonet joint connection with the cover or support 26. The connection between the annular connecting member 33 and the supporting member 26 is effected by means of a pair of oppositely located ears or projections 34 and the ring 33, which extend outwardly from the ring 33, and can be inserted through the oppositely located notches 35 (Fig. 3) in the supporting plate 26, and then turned to bring the ears 34 behind the plate 26. The edges of the circular opening 36, from which the notches 35 extend, are bent inwardly to form a pair of helical cam edges 37 for engagement with the laterally extending ears 34 of the connector ring, so that as the connector ring is rotated the helical edges 37 will cause the ring to be drawn inwardly to force the plug-in device 31 snugly into engagement with the cover plate 21 of the receptacle 15. The engagement between the connector ring 33 and the supporting plate 26 is thus a sort of combination of bayonet joint connection and screw-threaded or helical cam action, whereby a quick connection is effected, and also a binding engagement such as would be obtained by screw connection if effected. The swivel engagement of the connector ring 33 with the plug-in device 31 is effected by the engagement of the inwardly extending flange 38 of the connector ring with the annular shoulder 39 on the insulating base 40 of the plug-in device. The connection between the supporting bracket 32 and the swivel connector ring 33 is effected by providing the bracket 32 with a yoke portion 41 which straddles the swivel connector ring and engages behind the outwardly extending annular beaded portion 42 of the connector ring. This outwardly extending annular beaded portion 42 of the connector ring not only serves as a retaining member for the yoke 41 but also serves as a thumbpiece or handle for screwing or rotating the connector ring to connect it with the supporting plate 26.

The connection between the fixture 17 and the supporting bracket 32 is effected by the engagement with the upwardly extending post or projection 43 of the bracket 32, with a transversely extending strap 44 which is secured to the canopy 45 of the fixture 17. In some instances it is desirable to provide insulation between the strap 44 and the post 43, which may be effected by means of a piece of sheet fibre bent to straddle the strap at the point adjacent the post 43.

In order to make the construction as compact as possible, the insulating base 40 of the plug-in device may be provided with a frusto-conical boss portion 46 which extends into a correspondingly shaped depression in the cover 21, this boss portion 46 being

provided with recesses 47 to provide clearance for and access to the binding screws 48, threaded into the contact blades 23.

The cover or supporting plate 26 may be secured to the outlet box 15 by means of a pair of screws 49, which extend through openings in the plate 26 and are threaded into ears 50 extending outwardly from the outlet box 15. In this construction it will be noted that the fixture 17 and the plug-in device 31 are both supported by the swivel connector ring 33 independently of each other, so that the strain of supporting the fixture 17 does not come on the plug-in device 31, but is taken care of directly by the connector ring 33. It will also be noted that the connection between the swivel connector ring 33, and the supporting plate 26 may be quickly effected by partial rotation of the swivel ring and that this connection forces the plug-in device 31 tightly into engagement with the cover 21.

In order to keep the yoke member 32 from slipping around on the swivel connecting ring 33, the yoke member is provided with an inwardly extending lug 51, which slips into the notch 35, previously referred to, when the parts are assembled.

To make the connection, the combination electrical connector and fixture supporting device is placed in proper position with respect to the receptacle, so that the blades 23 will enter into engagement with the contact devices 20. The swivel ring 33 is placed so that the ears 34 will register with the notches 35 and this ring is then pushed in and turned to move the ears 34 back of the plate 26, the ears 34 engaging the helical edges 37 to force the plug-in device 31 into proper position with respect to the receptacle 16. The fixture 17 is then simply hung on the post or hook 43 of the supporting bracket 32, the wires 51^a being slack enough to permit the above method of assembly.

In Fig. 6, the construction is substantially the same as in the form previously described, except that here the fixture supporting bracket 52 is permanently secured to the transversely extending strap 53 of the fixture 54 in any suitable manner as by means of rivets 55.

In Figs. 7 and 8, the construction is substantially the same as in the form previously described, except that here the swivel connecting ring 56 is provided with a flaring collar or neck 57 which forms an annular channel to receive the yoke member 58 to which the transversely extending strap 59 is secured.

In Figs. 9 and 10 the construction is substantially the same as in the form previously described, except that here the fixture supporting bracket 60 has inwardly struck fingers 61, which engage inside the inwardly

extending flange 62 of the swivel connector ring 33. In this form in order to keep the supporting bracket 60 in upright position, the insulating base 40 is provided with a recess 63 into which the inwardly extending finger extends.

What I claim as new and desire to secure by Letters Patent of the United States is:—

1. A side wall fixture construction comprising a flat flush plate having a circular opening therein, a receptacle mounted behind said plate having a portion extending across said opening substantially flush with said plate, a plug-in device having contact blades insertable through said opening into engagement with the receptacle contacts, a fixture electrically connected with said contact blades, and means for securing said fixture in position with respect to said receptacle, comprising a ring swiveled about said plug-in device, said ring and plate being provided with bayonet joint connecting means, the edge of said opening being bent

inwardly to provide a helical cam surface whereby said ring will be drawn toward 25 said receptacle in making the connection.

2. A side wall fixture construction comprising a flat flush finishing plate having a circular opening therein, a receptacle mounted behind said finishing plate having a portion extending across said opening substantially flush with said plate, a plug-in device having contact blades insertable through said opening into engagement with the receptacle contacts, a fixture electrically 30 connected with said contact blades, and means for securing said fixture and plug-in device in position with respect to said receptacle, comprising a ring swiveled about said plug-in device and a yoke to which said fixture is secured, straddling said ring and having a swivel connection therewith.

In witness whereof, I have hereunto subscribed my name.

REUBEN B. BENJAMIN.
